UNITED STATES PATENT OFFICE.

CHARLES R. KEERAN AND MICHAEL M. KAUFMANN, OF CHICAGO, ILLINOIS,
ASSIGNORS, BY MESNE ASSIGNMENTS, TO AUTOPOINT PENCIL COMPANY,
OF CHICAGO, ILLINOIS, A CORPORATION OF ILLINOIS.

PENCIL.

1,400,362.

Specification of Letters Patent. Patented Dec. 13, 1921.

Application filed June 9, 1919. Serial No. 302,757.

To all whom it may concern:

Be it known that we, CHARLES R. KEERAN and MICHAEL M. KAUFMANN, both citizens of the United States, residing at 5 Chicago, in the county of Cook and State of Illinois, have invented certain new and useful Improvements in Pencils, of which the following is a specification.

This invention relates to a pencil equipped 10 with propelling mechanism interiorly of its body, and operable by means exteriorly thereof, for advancing into operative position a lead at one end, and an eraser at the other.

15 In many ways the present pencil is similar to the constructions already disclosed in certain applications now pending as Serial Nos. 213,241, 272,054, and 291,494; it exhibits, however, certain distinct improvements, particularly as to details of manufacture and assembly. It is to be understood, therefore, that the pencil to be herein described embodies many of the features claimed in the applications aforesaid, as 20 well as certain other improvements to which specific reference will hereinafter be made.

In the accompanying drawing certain exemplifications of this invention are shown in the manner following:

30 Figure 1 is a longitudinal section through a pencil whose body is solid, the operating parts being shown in elevation;

Fig. 2 is a similar view through a pencil having a hollow tubular body, the operating parts being shown partly in section;

Fig. 3 is an enlarged detail, in longitudinal section, exhibiting the parts in the upper end of the pencil illustrated in Fig. 1, the propelling plunger being shown as re- 40 tracted close to its limit;

Figs. 4, 5, and 6 are transverse sections through the pencil, taken respectively on line 4—4 of Fig. 3, line 5—5 of Fig. 2, and line 6—6 of Fig. 3;

45 Fig. 7 is an elevation of the upper portion of the tube by which the propelling plunger is operated; and

Fig. 8 is a perspective view of the clip, detached from the pencil body.

50 In the use that is herein made of the terms "upper" and "lower," it should be

understood that we are referring to the pencil as it is pointed in use—that is, with the eraser end up, and the writing end down.

As illustrative of a desirable construction, there is shown in Fig. 1 a pencil having a solid body 11 which is provided with a central bore adapted to receive a tube 12 in which propelling mechanism is contained. At the lower extremity of the tube is a tip 13 provided with an axial bore, and arranged to abut a ferrule 14 that caps over the lower end of the pencil body. The bore within the tip is suitably constricted to provide a passage of proper size to frictionally engage a lead A that may be used in the pencil.

Throughout the lower portion of the tube which is non-rotatably secured within the pencil, are one or more internal ribs, preferably in the form of flutings 15. A plunger 16 having a threaded body is arranged for longitudinal travel within the tube, being formed with a lateral fin 17 adapted to lie adjacent one or more of the flutings. 75 In such a construction the plunger is guided non-rotatably, as it travels longitudinally through the pencil, to propel in advance of itself a lead. Overlying the upper end of the body is a cap 18 having its sides offset, as shown, to provide an upper part 19 that is externally threaded to receive in flush relation with the body a collar 20; the lower portion 21 of the cap, by preference, lies flush with the collar, and with the body as well, which is suitably recessed for this purpose. The top side of the cap is centrally apertured to receive the upper extremity of the tube 12 whose end may conveniently be upset, or hammered down, or spun out, as at 22, to overlie the cap. It will be noted that through the medium of the ferrule and tip at the lower end, and the cap at the other, the tube is firmly secured against longitudinal movement with- 90 in the body.

A magazine is arranged within the pencil which, in the form shown, consists of a plurality of chambers 23, preferably four in number, arranged in radial relation to the 100 tube 12. Each chamber is in the form of a slot extending from the upper end of the

body down for a distance about equal to the length of one or more leads. When the cap 18 is arranged in place, the upper ends of these slots are closed, except for the 5 openings that are arranged in the cap, one in register with each slot to permit reserve leads B to enter and leave the chambers of the magazine.

Means are provided for locking the cap 10 against rotation relative to the body consisting preferably of a plurality of ribs 24 arranged parallel to the axis of the pencil and projecting interiorly of the cap into substantial alinement with the interior surface 15 face of its upper portion 19. These ribs coöperate with complementary grooves or channels formed exteriorly of the pencil body, the relation of the parts being such as to provide an interlock which positively 20 prevents rotation of the cap upon the pencil. Upon the cap so mounted in place, the collar 20 may be threaded. It will be noted that the upper end of the collar is inturned to provide a flange 25, whose upper surface 25 affords a bearing for a sleeve 26 in which is retained an eraser 27. Interiorly of this sleeve are formed threads 28, as shown in Fig. 3. At the lower end of the sleeve is a transverse wall 29 having a central aperture 30 from whose periphery depends a flange 30. The abutting portions of the collar and sleeve are so formed that the collar flange 25 will underlie the sleeve wall 29, and at the same time present its inner edge adjacent the flange 30 depending therefrom. By 35 this means the parts are correctly centered, and permitted to rotate, one with respect to the other.

A connection is provided between the 40 collar 20 and sleeve 26 which, according to the form shown, consists solely of a tube 31 which serves also as the operative connection between the propelling plunger 16 and its actuating member, the eraser sleeve. At the 45 lower end of this tube 31 are interiorly formed threads 32 arranged to coöperate with the threaded body of the plunger. The upper end of the tube 31, however, is so formed as to establish an inseparable, but 50 freely rotatable, connection between the collar 20 and sleeve 26, and also an inseparable, but non-rotatable, connection between itself and the eraser sleeve. These 55 ends are attained by slightly expanding the tube as at 33, forming thereon an annular bead 34 upon which may rest a washer 35, and reshaping the walls above the bead as at 36, to take on a cross section that is polygonal, and by this term we mean some formation other than round. It should be mentioned that the aperture formed within the 60 transverse wall 29 and depending flange 30 is also polygonal so as to coöperate with the complementary walls 36 of the tube 31, the 65 effect being to prevent relative rotation be-

tween the collar and eraser sleeve. When the parts are related in this manner, the end of the tube 31 may be upset, spun out, or otherwise deformed as at 37, to overlie the transverse wall 29, an annular groove being 70 preferably provided to receive the turned out end of the tube. The use of the washer 35 which is intended primarily to abut the lower end of the depending flange 30, prevents binding between the collar and eraser 75 sleeve, so that these two parts may at all times be freely rotatable one with respect to the other. The connection thus made is inseparable, it answers fully the requirements of our invention, and represents a 80 minimum of cost, as well as certainty in operation. The collar and eraser sleeve thus maintained in connected relation constitute for the pencil a head, one element whereof serves as the means for detachably connecting with the pencil body, and the other as the means for actuating, through the medium of the tube 31, the propelling mechanism within the pencil.

Threaded within the sleeve 26 is a plate 38 90 having a socketed boss 39 interiorly threaded to coöperate with the upper end of the plunger 16 when this element is sufficiently retracted for such a purpose. The boss is free to enter slightly into the expanded 95 upper end 36 of the tube 31 as required (see Fig. 3) when the plate 38 is in its lowermost position. By rotating the eraser sleeve properly, the plunger 16 may be retracted until it engages with the plate which 100 is thereupon held against further rotation; continued turning movement of the eraser sleeve will then result in relative rotation between itself and the plate such that the latter is caused to move outwardly to propel 105 in advance of itself the eraser.

Reference will now be made to a clip 110 which is characterized by several features of novelty. As best shown in Fig. 8, this clip is formed with the usual body portion 40 having a foot 41 adapted to press against the side of the pencil, the upper end of the clip body being curved to provide a shoulder portion 42 upon which is carried a head 43 flanged on either side as at 44. A clip 115 so formed may be conveniently attached to the pencil of Fig. 1 by providing in the wall of its body immediately below the cap 18 a slit 45 communicating with one of the chambers 23 therein, which is also recessed back to the cap wall 21, as shown in Fig. 3; within such a recess the head of the clip may lie between two of the ribs 28 with its flanges 44 in abutting relation to the tube 12, and in countersunk relation to the 120 walls of the chamber 23 so as not to obstruct the space therein afforded for reserve leads, the shoulder portion 42 of the clip lying within the slit 45 adjacent the lower edge of the cap wall 21 to present the clip 125 130

body exteriorly of the pencil. It will be manifest that a clip of such formation when secured to the pencil as explained, will be immovably held in place, and the manner 5 of its attachment will also be effectually concealed.

The preceding description has been concerned in large part with a pencil having a relatively solid body, as distinguished from 10 a hollow tubular body, such as is generally formed of metal. The pencil may be formed, however, with a tubular body such as is exhibited in Fig. 2, having operating parts in 15 all respects the same as those described in connection with the remaining figures. Accordingly, the same reference numerals have been applied to the corresponding parts, and it is unnecessary to specifically advert to them again.

20 Referring now to the construction shown in Fig. 2, the body, designated as 50, is tubular in form, being provided with a tapered lower end 51 having at its extremity a tip 52 which may conveniently be connected to 25 the tube 12 within the body. In the region where the taper commences, is a transverse brace plate 53 which affords a bottom for the magazine of the pencil, which, by preference, is divided into four compartments (see Fig. 30 5) through the use of suitable partition members. Each of these partition members may consist of two radially disposed walls 54 connected by an arc shaped wall 55 extending from the upper end of the 35 pencil down close to the brace plate 53. In practice, it is preferred that these partition members should be formed of some material that is light, thin, and slightly resilient, such as aluminum, so that they may be sprung 40 into place and be held firmly therein against movement by their own spring action. The upper end of the body may be capped over, its walls adjacent thereto being preferably inset and threaded as at 56 to receive the pencil 45 head which is formed in all respects the same as has been described in connection with Fig. 3.

According to our invention certain economies are effected in the manufacture and assembly of this pencil, it being unnecessary 50 to resort to soldering in any instance for the purpose of establishing permanent connections. All the requirements of the present pencil are fully satisfied by utilizing this in-

vention which is productive of economies 55 both in time and labor.

We claim:

1. A pencil having within its body lead propelling mechanism, and exteriorly of its body a rotatable actuating means therefor 60 including a collar and sleeve arranged end to end, the former stationary and the latter rotatable with respect to the body, the adjacent ends of the collar and sleeve being formed with transverse walls each having a 65 central aperture, one such wall being flanged to lie within the aperture of the other, and having its inner periphery polygonal in character, and a tube extending through the polygonal aperture of the flanged wall having 70 its surface adjacent thereto of like polygonal formation, the tube walls adjacent each end of the flanged wall being outwardly extended to hold the collar and sleeve in inseparable relation, the tube being extended 75 within the pencil to maintain operative relation with the propelling mechanism, substantially as described.

2. A pencil having within its body lead propelling mechanism and actuating means 80 therefor including a sleeve and collar in end to end relation, the former having an inwardly extending flange, and the latter being arranged to detachably connect with the body, and a single means of connection between the sleeve, collar, and propelling mechanism consisting of a member having a cross section that engages non-rotatably with the sleeve flange, rotatably with the collar, and operatively with the propelling mechanism, the longitudinal configuration of the member being such as to lock the sleeve and collar inseparably together, substantially as 85 described.

3. A pencil having a body at the upper 95 end of which is a cap whose cylindrical walls are provided with inwardly projecting ribs adapted, when fitted upon the pencil, to enter the pencil body to interlock therewith, and a head rotatably mounted on the pencil adapted to actuate lead propelling mechanism interiorly thereof, there being means provided with a threaded connection for securing the head to the cap, substantially as described.
